[57] CLAIM

The ornamental design for a combined clipboard and stationery supply case, as shown and described.

DESCRIPTION

FIG. 1 is a top, right front perspective view of a combined clipboard and stationery supply case showing my new design;
FIG. 2 is a top plan view drawn to an enlarged scale;
FIG. 3 is a bottom plan view of FIG. 2;
FIG. 4 is a rear elevational view of FIG. 2;
FIG. 5 is a front elevational view of FIG. 2; and
FIG. 6 is a right side elevational view of FIG. 2, the left side being a mirror image thereof.

FIG. 2

FIG. 3

FIG. 4

FIG. 5

FIG. 6
